EUGÈNE EBERSOL, OF MULHOUSE, FRANCE, ASSIGNOR TO SOCIETY FRERES KOECHLIN,
OF MULHOUSE, HAUT-RHIN, FRANCE.

PROCESS FOR PRINTING UPON TEXTILE FABRICS.

Application filed May 18, 1925, Serial No. 31,194, and in France June 16, 1924.

The process which is most frequently employed for the printing of textile fabrics in roller printing machines consists in principle in passing the piece of material to be printed between two rollers whereof one is a copper roller carrying designs on which the coloring matter is disposed, and the other is a pressure roller which is usually of a larger size.

To obtain the proper results, it is necessary to wind upon the said pressure roller several layers of a soft fabric, or lapping, and to employ an endless band of a felted or rubber covered cloth.

In order to prevent the endless band from being soiled to an improper degree due to an excess of colour, it has been found quite necessary in the known devices—exclusive of certain arrangements which are not in general use and have nothing in common with my invention—to employ an absorbing member consisting of cotton cloth and serving to take up the excess of coloring matter which traverses the work piece or issues at the sides of the same when the said piece is narrower than the engraved part of the printing roller.

The said absorbing member must be frequently washed and dried in order to be used for succeeding operations. It is obvious that such repeated washing and drying operations will occasion an increased expense as regards labor, power, water, and the like, besides wearing out the said member which can only be replaced at a considerable expense.

Attempts have been made to utilize a water-proof member for receiving the excess of color, it being freed in the machine itself from the excess of color which it receives, by means of adequate washing and drying devices. But a member of this kind has a small absorbing power, so that its efficacy is much reduced.

In my invention, I replace the said absorbing member with an endless band of wire gauze which will readily absorb the excess of the coloring matter and can be washed and dried with great facility within the machine itself.

The appended drawing shows by way of example one embodiment of my said invention. On the pressure roller B is mounted the lapping H on which comes to bear successively the endless belt or conveyor D, the absorbing belt A and the piece of fabric C

which is to be printed. In the present invention the absorbing belt A is represented by a fine metallic gauze. This receives the excess color from the printing rollers F' which traverses the fabric C. The said wire gauze member receives the excess of the coloring matter—in the same manner as the known absorbing member—and it may be freed from this coloring matter by an arrangement of brushes, optionally followed by a washing device E, or like means. The said wire gauze member can be readily dried by utilizing the heat of a drying drum F or of the heating chamber. The major part of its moisture can be expelled by suction or blowing. After being subjected to this treatment, the said wire gauze member continues upon its course and returns to the machine for reuse.

It should be noted that the said wire gauze member may in the present example be employed with an endless band D or it may be employed alone and without any endless band or any lapping.

The endless band can be replaced by a coating of rubber or like substance on the pressure roller.

In my said process I obtain the following advantages.

1. The usual absorbing member is entirely dispensed with.

2. For this reason I eliminate all that labor required in the operation of the color printing machine, comprising the observation of the operation of the absorbing member which is subject to the frequent creasing of the work piece, as well as for the transportation, washing, and repairing of the absorbing members.

3. All equipment pertaining to such operations is eliminated.

4. The machine may operate with a much shorter endless band for instance 8 meters instead of 40 meters, or the said band may even be eliminated.

5. The machine may be operated with the use of much thinner colors, thus affording an economy as concerns the thickening of the same (i. e. facility of evaporating and washing) from the fact that the meshes of the said wire gauze member will readily absorb the excess of color, thus greatly reducing the flattening or sinking and thus augmenting the relief of the printed design. The pressure of the roller may thus be considerably

reduced, and I obtain an easier operation, a saving in power, and a diminution of the spreading of the coloring matter upon the piece of work.

5 6. The operation is quite continuous.

7. All traces of the seams of the absorbing member upon the piece of work are eliminated.

10 8. I obtain a great saving in coloring substances, since the process affords darker tones than otherwise for a like treatment.

Having now particularly described my invention and the manner in which the same is to be performed, I declare that what I

15 claim is:

1. In apparatus for printing textile fabrics, a pressure roller and an endless belt of metallic gauze between this pressure roller

and the piece of fabric to be printed for absorbing the excess color.

2. In apparatus for printing textile fabrics, a pressure roller, a lapping of elastic material on said roller, and an endless band of metallic gauze between said lapping and the piece of fabric to be printed for absorbing excess color.

3. In apparatus for printing textile fabrics, a pressure means, and color supplying means and an endless belt of metallic gauze for absorbing excess color, travelling with the fabric to be colored between the pressure means and the color supplying means.

In testimony whereof I have signed my name to this specification.

EUGÈNE EBERSOL.
